[57] **CLAIM**

The ornamental design for a grooved golf driver, as shown and described.

DESCRIPTION

FIG. 1 is a view of a grooved golf driver showing my new design taken along lines 1—1 of FIG. 4;

FIG. 2 is a view taken along lines 2—2 of FIG. 5;

FIG. 3 is a view taken along lines 3—3 of FIG. 5;

FIG. 4 is a left side elevation thereof;

FIG. 5 is a front elevation thereof;

FIG. 6 is a right side elevation thereof;

FIG. 7 is a top plan view thereof;

FIG. 8 is a bottom plan view thereof;

FIG. 9 is a fragmentary front elevational view thereof;

FIG. 10 is a fragmentary left side elevational view thereof;

FIG. 11 is a fragmentary right side elevational view thereof;

FIG. 12 is a fragmentary top plan view thereof; and,

FIG. 13 is a fragmentary bottom plan view thereof.
